UNITED STATES PATENT OFFICE.

HENRY M. MYERS, OF BEAVER FALLS, PENNSYLVANIA.

MACHINE FOR SPLITTING THE TANGS OF SHOVEL-BLANKS.

SPECIFICATION forming part of Letters Patent No. 367,833, dated August 9, 1887.

Application filed March 4, 1887. Serial No. 229,709. (No model.)

To all whom it may concern:

Be it known that I, HENRY M. MYERS, a citizen of the United States, residing at Beaver Falls, in the county of Beaver and State of Pennsylvania, have invented certain new and useful Improvements in Machines for Splitting the Tang and Forming the Socket of Shovel-Blanks; and I do hereby declare the following to be a full, clear, and exact description of the invention, such as will enable others skilled in the art to which it appertains to make and use the same.

My invention relates to an improvement in machines for splitting the tang for the handle- straps and forming the socket in the blanks for making shovels, spades, and scoops; and it consists in the constructions hereinafter described, and particularly pointed out in the claims.

20 In the accompanying drawings, which form a part of this specification, Figure 1 represents a plan view, partly in section; Fig. 2, a longitudinal section on the line 2 2 of Fig. 1; Fig. 3, a transverse section on the line 3 3 of Fig. 1; and Fig. 4 is an enlarged perspective showing a blank in a stirrup for supporting it.

Reference being had to the drawings and the letters marked thereon, A represents the bed of the machine, which is supported upon suitable legs and has a recess formed in its upper side, in which the blank-clamping and tang-supporting jaws operate.

B represents the cheek-pieces, which are adjustable laterally by means of screws a, and are held to the bed A by bolts b, which pass through the elongated apertures c, and are cushioned and held to their proper working position by springs d.

C represents the longitudinally movable blank-clamping and tang-supporting jaws, which are provided with one straight face, e, and an inclined face, f, which latter bears against the corresponding inclined face, g, of the cheek-pieces B. The jaws C are cushioned and returned by coiled springs h, the tension of which is regulated by a follower, i, and a screw, k. The inner ends of the jaws are cut away at l to allow the metal of the tang of the blank to bend outward as the knife penetrates the tang, and form supports for the bifurcated arms 4 5 of the tang, which, when rolled out, form the handle-straps of the shovel.

D represents shovel-blanks in position on the machine and supported in stirrups E, which are provided with a follower-plate, m, adjusted 55 by screws n, and a detachable plate, o, which prevents the blank from falling out of the stirrup. In the rear of each blank as it stands in the machine is a follower, F, which is adjusted longitudinally by a screw, p, and holds the 60 blank in position for the sliding jaws C to clamp it as they are moved in one direction. G represents a hand-lever, which is pivoted to the support q, and is adapted to be thrown across the machine, as shown in dotted lines 65 in Fig. 1 and in full lines in Fig. 3, with a portion of its lower side resting upon the upper end of the blank and the end of the lever near the handle engaging with hook or dog r. The function of this lever is to prevent the cutter 70 from throwing the blank out of the machine when the cutter first strikes it from the under side, and to assist in holding the blank while the tang is being split.

H represents a shaft mounted in suitable 75 journals on the bed A, and upon said shaft are mounted eccentric cams I I and an eccentric cutter, K.

L represents a shaft which supports a driving-pulley at one end, and a pinion, s, on the 80 opposite end, which engages with a master-wheel, t, on the shaft H. The shaft H also supports a balance-wheel, M.

The several parts being constructed substantially as described, the operation is as follows: The blanks D are heated and placed in position in the machine and power applied to the driving-pulley. The shaft H as it revolves brings the cutter K in contact with the tang, splitting it down to and sufficiently beyond the 85 root of the tang to form the socket and the handle-straps. The cams I I at the same time operate the tang-supporting and blank-clamping-jaws C by moving them out from the shaft H as the cutter K advances into the tang. The 90 cut-away portions l of the jaws support the arms 4 5 of the tang and prevent the cutter from running off to one side or the other of the tang, thus securing a uniform thickness of the handle-straps. While the tang of one 95 blank is being cut the jaws on the opposite end of the machine are being thrown toward the shaft H by the springs h and the blank released, when it is removed by the operator.

Instead of returning the jaws C by means of the springs h, they may be connected by a yoke engaging both jaws in the same plane, and also engaging the cam I, thus producing 5 a positive movement of the jaws in both directions.

Having thus fully described my invention, what I claim is—

1. In a machine for splitting shovel-blanks, a 15 revolving cutter for splitting the tang, in combination with reciprocating jaws for clamping or holding the blank and supporting the tang laterally while being split, substantially as described.
- 15 2. In a machine for splitting shovel-blanks, a cutter eccentrically mounted upon a shaft, in combination with reciprocating jaws for clamping or holding the blank and supporting the tang laterally while being split, and an eccentric cam for operating said jaws, substantially as described.
- 20 3. In a machine for splitting the tang of shovel-blanks, a cutter mounted upon a shaft, reciprocating jaws for clamping or holding the 25 blank and supporting the tang laterally while

being split, and means for moving the jaws, in combination with cheek-pieces, substantially as described.

4. In a machine for splitting the tang of shovel-blanks, the combination of a cutter 30 mounted upon a shaft, a stirrup for supporting the blank, reciprocating jaws for clamping the blank and supporting the tang laterally while being split, and suitable means for operating said jaws, substantially as described. 35

5. In a machine for splitting the tang of shovel-blanks, a cutter mounted eccentrically upon a shaft, and suitable means for revolving the same, substantially as described.

6. In a machine for splitting the tang of 40 shovel-blanks, a stirrup for supporting a blank, provided with an adjustable follower, in combination with a lever for holding said blank, substantially as described.

In testimony whereof I affix my signature in presence of two witnesses.

HENRY M. MYERS.
